UNITED STATES PATENT OFFICE

SIMON REISLER, OF INDIANAPOLIS, INDIANA

MEANS FOR LIGATING ARTERIES

Application filed June 4, 1928. Serial No. 282,573.

The object of this invention is to seize and securely ligate a blood vessel at a distance inaccessible to the reach of the fingers during surgical operations, performing the act of tying a suitable double knot similar to one tied with the fingers.

An object of the invention is to transfer a loop previously applied over a hemostat, and tie it securely over the tissues caught by the hemostat, then tighten a second loop over the first, thus making a double knot which securely holds the blood vessel.

I accomplish the above and other minor objects which will hereinafter appear, by the means illustrated in the accompanying drawing, in which—

Fig. 1 is a top plan view of my apparatus threaded and ready for use by the surgeon.

Fig. 2, shows the same with the artery grasped and being held, the ligature being positioned around the artery, with the tying mechanism of the apparatus in position to tighten the ligature on the artery and tighten the first knot.

Fig. 3, shows a major portion of the tying mechanism or unit only, with the thread contacting ends of the legs crossed together to release the thread from the end hooks.

Fig. 4 is a top plan view of the hemostat with the tying mechanism removed.

Fig. 5 is a fragment of the mechanism shown in Fig. 3 turned upside down.

Fig. 6 is a cross section on the line 6—6 of Fig. 1.

Fig. 7 is a cross section on the line 7—7 of Fig. 4.

Fig. 8 is an edge view of the spring plate for locking together the two legs of the tying mechanism and

Fig. 9 is a perspective view of the knot tying mechanism positioned as shown from the line 9—9 in Fig. 2.

Like characters of reference indicate like parts in the several views of the drawings.

The end of any artery to be tied such as

that shown at 10, is grasped securely between the jaws 11, 11, of a hemostat preferably toothed to increase the hold. The power arms 12 of the hemostat are very long comparatively. The grip on the artery is retained by a suitable lock 13, here shown as a pair of interlocking hooks, see Fig. 7, of the "pressure release" type that locks with pressure of the hand and releases by a further pressure.

One of the arms 12 has an inside extension 14 formed with a slot 15 longitudinally of the arm and terminating at its inner end with an enlargement 16, for the passage through the slot of the flanged end of a lug 17, alined with a pivot 18, and preferably integral therewith, which connects the two legs 21 and 22, of a pair of knot-tying levers slidingly held by and on the hemostat.

The power arms 19 and 20 of the tying levers are shorter than the legs and are curved away from each other and terminate with finger-loops 23. The power arms are bent and positioned so they can cross each other instead of contacting when pressed together, in order to increase the outward movement of the ends of their legs as shown in Fig. 2, and push the loop out of the hooks.

The legs 21 and 22 have bends 24 which offset the ends inwardly or toward each other so the offset portions will cross preferably to the extent shown in Fig. 3, which is sufficient to force the loop of thread out of the hooks. This is regulated by contact of the two legs with each other at 25. But should it be desirable to cross the legs further that is readily accomplished by making the bends 24 closer to the pivotal point of the legs.

The legs 21 and 22 terminate with hooks 26 opening outwardly, and adjacent thereto are eyes 27. One of the finger loops 23 has a spring clamp 28 to hold the ends of the thread as shown in Figs. 1 and 2. Pivoted at one of its ends to the leg 21 is a curved spring plate 29 which is set to press against

the leg 22 at its other end. This last end is camfaced on its contacting side, see Fig. 8, to increase its frictional engagement with leg 22, and the engagement may be further increased by corrugations 30.

5 In the operation of my invention the thread 1 is looped around the hemostat and crossed for a single knot. Then the knot-tying member is positioned on the hemostat with its lug 17 in slot 15 and pushed out to the small end of the slot, legs 21 and 22 contacting, and finger loops resting upon the loops 23 of the hemostat as shown in Fig. 1, to hold the knot-tying member steadily and firmly. Then the thread-ends are crossed through the hooks for a second single knot (see Fig. 9), and are then threaded through the eyes 27 and are drawn taut and are fastened under the spring-clamp 28.

10 The instrument thus prepared, usually by an assistant, is ready for use by the surgeon who grasps the four loops with his thumb and three fingers and inserts the jaws into the cavity, firmly grasps the end of the artery to be tied between the jaws by a spreading movement of the loops 23, and locks the instrument on the artery by the aid of the pressure release lock 13.

15 Then changing the loops 23 to the left hand while holding those of the tying device in the right hand, the operator pushes the loop of thread around the hemostat, off of the latter upon the artery and draws the first knot tight by spreading the legs 21 and 22 apart approximately to the position shown in Fig. 2. Then the thread is disengaged from the hooks 26 by carrying the legs to the position shown in Fig. 3, which leaves the thread threaded through the eyes 27 and crossed between the eyes ready to finish the tie of a 20 double knot by tightening up the thread-ends held in clamp 28, and then again spreading the legs 21 and 22 apart. This completes the tying of a double knot of the same character as is usually tied by hand in ligating arteries.

25 My invention is useful in tying other than arteries and I do not desire to limit it in the matter of its use.

30 While I have shown and described a precise form of my invention it is capable of modifications without departing from the spirit thereof and I therefore do not desire to be limited to the form and operation shown, any more than is required by the appended claims, and having thus fully disclosed my invention what I claim is:—

35 1. In a ligating instrument, means for grasping an end of a member to be tied, a thread looped around said grasping means and crossed to form a second loop for a double knot, means for grasping the thread in the second loop, means for grasping it beyond the second loop, means for transferring the loops from the grasping means to the member to be tied, and means for con-

secutively tightening the two loops having a spreading action in one direction to tighten one of the loops on the member and having a spreading action in a reverse direction to release the first loop and engage the second loop for tightening into a double knot with the first loop.

40 2. The combination with a hemostat having a longitudinal slot, of a knot tying device having a lug movable longitudinally in the slot and removable therefrom, said knot-tying device comprising a pair of pivotally united levers.

45 3. The combination with a hemostat, of a knot tying device movable longitudinally thereof to transfer two loops previously applied to them from the hemostat to the object to be tied, said tying device having a spreading action in one direction to tighten one of the loops on the object and having a spreading action in a reverse direction to release the second loop for tightening into a double knot with the first loop.

50 4. The combination with a hemostat, of a knot tying device movable longitudinally thereof to transfer two loops previously applied to them from the hemostat to the object to be tied, said tying device having a spreading action in one direction to tighten one of the loops on the object and having a spreading action in a reverse direction to release the second loop for tightening into a durable knot with the first loop, and then by again spreading the device to tighten the second loop with the first into a double knot.

55 5. The combination with a hemostat of means adjustably and removably secured thereto for transferring two previously formed loops from them to an object to be tied to form a double knot, said last means having means for successively tying the two transferred loops into a double knot.

60 6. The combination with a hemostat of means for transferring two previously formed loops from them to an object to be tied to provide a double knot and means for successively tying the two transferred loops into a double knot by a spreading action of the last means followed by a reversing and crossing action and then by a second spreading action.

65 7. The combination with a hemostat of means for transferring two previously formed loops from them to an object to be tied, one loop to surround the object and the other for tying a double knot, and means for successively tying the two transferred loops by a spreading action of the last means followed by a reversing and crossing action and then by a second spreading action, comprising a pair of pivoted legs each having an eye and an end hook beyond the eye in which the thread is held.

70 8. The combination with means for holding the object to be tied, said means having a

slot, of a knot tying device slidably and removably secured in the slot, said device comprising a pair of pivoted legs each having a manipulating arm at one end and an eye and adjacent hook at the other end in which eyes and hooks the thread previously applied in a double loop is held, one of the loops passing initially around the object-holding means while the other is simultaneously placed in position for tying a double knot.

10. In testimony whereof I affix my signature.
SIMON REISLER.
